United States Patent

Des. 238,294
Patented Dec. 30, 1975

238,294

BRACELET

Alfred Joseph Durante, 111-46 76th Drive,
Forest Hills, N.Y. 11375

Filed Apr. 24, 1974, Ser. No. 463,751

Term of patent 14 years

Int. Cl. D11—01

U.S. Cl. D45—4 C

FIG. 4

FIG. 2

FIG. 1

FIG. 3

FIG. 5

FIG. 1 is a front elevational view of a bracelet showing my new design, the rear being a mirror image thereof;

FIG. 2 is a left side elevational view;

FIG. 3 is a right side elevational view;

FIG. 4 is a top plan view; and

FIG. 5 is a bottom plan view.

I claim:

The ornamental design for a bracelet, as shown and described.
